UNITED STATES PATENT OFFICE.

WILLIAM HARROP, OF NEW BEDFORD, MASSACHUSETTS, ASSIGNOR TO THE FISK RUBBER COMPANY, OF CHICOPEE FALLS, MASSACHUSETTS, A CORPORATION OF MASSACHUSETTS.

RING TRAVELER.

Application filed February 16, 1926. Serial No. 88,544.

This invention relates to improvements in ring travelers for twisting machinery. It has for its object a traveler which, as compared with prior devices, will produce a more uniform quality of yarn both as to size and degree of twist and will enable the traveler to be run continuously for longer periods of time with less frequent lubrication. These results are accomplished by improving the lubricating qualities of the traveler as I will particularly point out below.

Referring to the drawings:—

Fig. 1 is a perspective view showing the improved traveler in the position it assumes in actual use;

Fig. 2 is a perspective view showing the traveler by itself; and

Fig. 3 is a sectional view taken on line 3—3 of Fig. 2.

Twisting machinery consists generally in a driven spindle 10 located centrally within a twister ring 11. Mounted on the ring, as clearly shown in Fig. 1, is the traveler 12 which is bent around the ring to hold itself in place. As the spindle rotates, the yarn 13 which is looped under the upper side of the traveler causes the latter to travel with extreme rapidity about the ring in the direction shown by the arrow 14.

Variations in the friction which the traveler has upon the ring will cause a variation in the tension imposed upon the yarn with a consequent variation in size and twist given to the latter. It is necessary to lubricate the inner surface of the twister ring very frequently, generally at every doff, and sometimes more often. If too long a period is allowed to elapse between lubricating, it is found that the friction of the traveler on

the ring will vary to such an extent that the yarn is not uniform in quality.

Referring in particular to Fig. 3, my invention resides in providing the leading edge of the traveler with a recess 15, preferably extending the whole length of that part of the traveler which is adjacent the inner surface of the ring. When the twister is started after the ring has been lubricated, this recess immediately fills itself with grease which it picks up from the inner surface of the ring. In further operation of the twister this recess gives up its grease as the traveler becomes warm through the friction of its motion. This continuous lubrication keeps the traveler in proper condition for a much longer period than is possible with the old style travelers. Furthermore, the continuous lubrication keeps the traveler at all times under uniform friction conditions, resulting in a much more uniform product. I have found in practice that it is possible to run my improved traveler twice as long between lubrications as was possible with travelers constructed according to the older practice.

Having thus described my invention, I claim:—

1. A ring traveler having a lubricant receiving recess opening into the leading edge of the traveler.
2. A ring traveler having a lubricant receiving recess extending the full length of the traveler.
3. A ring traveler having a lubricant receiving recess located at the leading edge of the traveler and extending substantially throughout its length.

WILLIAM HARROP.
